UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY DRAFT RIGGING.

Application filed May 26, 1920. Serial No. 384,439.

To all whom it may concern:

Be it known that I, JOHN F. O'CONNOR, a citizen of United States, residing at Chicago, in the county of Cook and State of Illinois, have invented a certain new and useful Improvement in Railway Draft Rigging, of which the following is a full, clear, concise, and exact description, reference being had to the accompanying drawings, 10 forming a part of this specification.

This invention relates to improvements in railway draft riggings.

In the art of railway draft riggings, one of the common types of so-called attachments has involved the use of removable or detachable horizontally extending keys, some of which have been subjected to the loads occasioned by the buffing and pulling shocks. Some of these attachments have employed one key in addition to the usual coupler key and others have employed two such additional keys, one to sustain the buff and the other to sustain the draft loads. The key type of attachments for draft riggings 20 possesses certain advantages, particularly with respect to the detachability or removability of all the parts to facilitate inspection, repairs, etc. The key type of attachments however has given rise to a serious objection because of the fact that the keys, when subjected to excessive or abnormal loads, have a tendency to bend or buckle, thus destroying the efficiency of the draft rigging and making it difficult to remove the 25 keys when desired. The size of the keys which can be employed in draft riggings is, of course, limited by practical considerations, particularly the amount of metal which can be cut out of the draft sills, with the result 30 that the standard key now is generally made of a cross section $6'' \times 1\frac{1}{4}''$ or $1\frac{1}{2}''$. The reason keys, in draft riggings heretofore, have failed under excessive loads is due to the fact that the keys are supported at their 35 ends in or at the sills and the loads are applied centrally of the key which thus permits of large bending moments being imposed upon the keys.

The object of my invention is to provide 50 a draft rigging of the so-called key attachment type wherein is retained all of the advantages of the key type of attachments heretofore obtainable and wherein I eliminate the objections heretofore found in attachments of said type.

More specifically, the object of my invention is to provide a draft rigging employing attachments of the key type wherein the keys that sustain the shocks from the gear proper are made practically free from any bending moments and are subjected merely to shearing strains which are well within safe limits of shearing strains which keys of the standard type are adapted to sustain without substantial or appreciable injury. 60

The invention furthermore consists in the improvements in the parts and devices and in the novel combinations of the parts and devices herein shown, described and made the subject matter of claim. 65

In the drawing forming a part of this specification, Figure 1 is a part elevational vertical section, part side elevation of a portion of a railway draft rigging showing my improvements in connection therewith. And 70 Figure 2 is a horizontal sectional view corresponding substantially to the line 2-2 of Figure 1, the shock absorbing mechanism proper being shown in plan. 75

In said drawing, 10-10 denote channel 80 shaped center or draft sills of a railway car spaced the usual standard distance apart, said sills being provided with a front set of longitudinally extending key slots 11-11 and a second set of longitudinally extending 85 key slots 12-12. Mounted between the draft sills and rigidly secured thereto is a buffing or abutment block 13 adapted to sustain the buffing shocks. Where the sills are slotted, the webs of the channels are reinforced 90 by correspondingly slotted plates 14-14 riveted to the sills on the outer sides thereof.

The drawbar 15 is of standard type having a transversely extending slot 16 to accommodate the so-called coupler key 17 95 which extends through elongated slots 18 in the arms of a horizontal yoke 19 and through the sill slots 11. In normal position of the parts, the key 17 is located substantially centrally of the sill slots 11 and corresponding slots in the reinforcing plates 14 so that said key is adapted to move both inwardly and outwardly in accordance with the movements of the coupler. The forward arms of the yoke 19 are enlarged as indicated at 100 20 where the slots 18 are formed so as to provide wide bearings for the key 17 and also to bring such bearing portions, indicated at 21, closely adjacent the coupler shank and thereby eliminate or reduce to a 110

minimum the bending moments on the key 17 under draft. As shown, the yoke 19 remains stationary under buff so that the key 17 travels freely within the slots 18 without any load during buffing action. The key 17 is held against accidental removal by any suitable means as for instance the cotters 22-22.

Within the yoke 19 I have illustrated a well known type of friction gear designated generally by the reference A, said gear being of the friction type and bearing at its rear end against a follower 23 which is slotted on its side so as to be supported by the yoke and at its front end bearing against a front follower block 24. The follower block 24 will preferably be in the form of a casting and of substantially hollow rectangular box-like form. Said follower block is provided with top wall 25, bottom wall 26, front wall 27, rear wall 28, and end walls 29-29. Said end walls 29 are slotted to accommodate a second or draft key 30 which extends horizontally through said block and through the sill slots 12 and corresponding slots in the reinforcing plates 14. The inner faces of the front and rear walls 27 and 28 of the block will preferably be grooved as indicated at 31 to accommodate the edges of the key 30 as clearly shown in Figure 1. As will be seen from an inspection of Figure 2, the key 30 is normally located at the forward ends of the slots 12 and will bear against the webs of the sills and the aligned portions of the plate 14 as indicated at 32-32, said portions of the sills acting as front stops in conjunction with the key 30 as will be understood. As shown clearly in Figure 2, the block 24 is made of a width substantially equal to the space between the draft sills so that the outer walls or portions of the block will slide back and forth on the inner faces of the webs of the draft sills. With this construction, it is evident that, in draft, the load will be transferred to the block from the shock absorbing mechanism proper centrally of the block and, because of the construction just described, this load will be transmitted from the block to the key not only at the center thereof but at the outer ends thereof directly adjacent the sills. In this manner, the key 30 is relieved of substantially all bending moments and is subjected only to shearing strains because of the fact that the block slides against the inner faces of the draft sills. In this connection, it will be observed that the key is braced by the block throughout the entire length of the key between the draft sills and I thereby eliminate the disadvantage heretofore observed in draft riggings of the so-called key type.

The follower block 24 is provided with recesses 33-33 near opposite ends thereof

to accommodate the arms of the yoke 19, said slots being sufficiently enlarged, laterally, to permit the block being slipped over the enlarged ends 20 of the yoke arms. The arms of the yoke 19 will also be slotted as indicated at 34-34 to accommodate the key 30 and permit its movement rearwardly with respect to the yoke while the latter is being held during buffing action.

Although I have herein shown and described what I now consider the preferred manner of carrying out the invention, the same is merely illustrative and I contemplate all changes and modifications that come within the scope of the claims appended hereto.

I claim:

1. In a railway draft rigging, the combination with the draft sills and shock absorbing means; of a follower block at one end of the shock absorbing means; a horizontally extending key passing through said block and immovable with respect thereto in a direction parallel to the center line of the draft rigging, the sills being slotted to accommodate said key and prevent movement thereof in one direction from normal but allowing it to move in the opposite direction, said block having bearing engagement with said key immediately adjacent the sills on the side of the key nearest the shock absorbing means; and yoke acting means including, horizontally extending arms on opposite sides of the shock absorbing means, said block being provided with slots extending parallel to the axis of the draft rigging to accommodate said members of the yoke acting means.

2. In a railway draft rigging, the combination with draft sills and shock absorbing means; of a rear abutment block disposed between and rigidly secured to the sills; a horizontally disposed yoke adapted to bear at its rear end against said block, said yoke straddling the shock absorbing means; a front follower block in engagement with the forward end of the shock absorbing means, said follower block being slotted parallel to the axis of the draft rigging to accommodate the arms of said yoke; and a horizontally extending draft key movable under buff passing through slots in said follower block, yoke arms and draft sills, said follower block having bearing engagement with said key centrally thereof and near the ends of the key immediately adjacent the inner faces of the sills.

3. As an article of manufacture, a follower block for railway draft riggings, said follower block being horizontally slotted transversely to accommodate a key the walls of the slot which cooperate with the front and rear edges of the key being spaced to always engage the same, said block being provided also with slots near each end thereof

to accommodate the arms of horizontally extending yoke acting means, said last named slots extending at right angles to the key slot and intersecting the latter, the said 5 walls being unbroken between said second named slots.

4. As an article of manufacture, a follower block for railway draft riggings, said follower block being provided with slots 10 near each end thereof to accommodate the arms of a horizontally extending yoke acting means, the body of said block between said slots being continuous, said block be-

ing also provided with a horizontal slot to accommodate a key, said last named slot extending at right angles to and intersecting said first named slots, whereby the front and rear edges of said key will be supported near the ends and at the center of the block in both buff and draft. 15

In witness that I claim the foregoing I have hereunto subscribed my name.

JOHN F. O'CONNOR.
